FIG. 7.

FIG. 2.

FIG. 3.

William J. Longtin

UNITED STATES PATENT OFFICE

2,103,625

HOSIERY

William J. Longtin, Reading, Pa., assignor to Infant Socks Company, Reading, Pa., a corporation of Delaware

Application July 19, 1934, Serial No. 736,087

7 Claims. (Cl. 66—172)

This invention relates to tubular rib fabric for hosiery tops or for other uses and more particularly to fabric having designs formed by wrap threads individual to the outside rib wales.

5 It is an object of this invention to provide an elastic garter section or sections in the wrap design tubular rib top for holding the same on the leg of the wearer, which garter section or sections comprises a plurality of continuous or non continuous courses of elastic rubber thread inlaid in the courses between the outside and inside rib wales.

10 It is a further object of this invention to securely anchor the ends of the inlaid rubber yarn 15 to the rib fabric so as to prevent creeping of the rubber yarn along the courses when the rib fabric is stretched in use.

15 A preferred embodiment will be described in connection with the accompanying drawing from which the advantages and objects of the invention will be obvious.

In the drawing:

20 Fig. 1 is a section in enlarged detail of a tubular rib wrap design top having an inlaid rubber yarn garter,

25 Fig. 2 is a view of a stocking or anklet showing the general location of the gasters, the rib top being unfolded, and

30 Fig. 3 is a similar view with the top folded to normal wearing position.

35 In the manufacture of tubular rib wrap tops of the type shown, by way of example, in Larkin Patent 1,772,400 and made upon the Larkin machine Patent 1,841,249, a wrap design thread and a finger for the same is provided for each cylinder needle, the design depending upon the wrapping or the non-wrapping of the design thread by the finger around the associated needle. In providing an inlay rubber thread, which may be 40 of the type known commercially as Lastex, to act as a garter in the completed article, there must be no interference between the design threads and the rubber yarn in the article and no interference between the operation of the 45 fingers and the rubber yarn inlay mechanism in the machine.

The mechanism whereby the combination of 50 rib wrap tops or fabric and rubber yarn garter inlay be made is shown in application Serial Number 736,088 filed July 19, 1934.

55 The wrap design rubber yarn garter inlay tubular rib tops may be used on infants' socks or hosiery or upon full length socks or hosiery. It may be used at any place where tubular rib fabric may have a function such as in sweaters, etc.

In Fig. 2 an infant's sock is shown having the plain foot 1 and the rib top 2 joined to the foot 1 at 3 in the usual manner. At 4, 5, and 6 are shown rubber yarn inlays of a number of courses, here shown as three, which depending upon the strength of the garter desired, may be any suitable number of one or more courses. The garter inlays may be placed wherever desired, that is only at 5 and/or 6 without 4 or only at 4 without 5 and 6. The rib top 2 is of the folding over type, folding on the line 7 to provide the top as shown in Fig. 3 having the wrap design indicated at 8 on the outer face. The folded over top conceals the inlays 5 and 6, and while the inlay 4 is shown diagrammatically in Fig. 3, 15 as being as prominent as inlays 5 and 6, actually the wrap design threads aid in concealing the inlay from view. The inlays 5 and 6 are not themselves prominent due to the coverage by the outside wales and the design threads makes the 20 inlay 4 even less prominent.

In the straight or unfolded type of rib top, the wrap design will appear as usual on the outside face and the inlays may be either below or above or at the design.

25 In Fig. 1 is shown a diagrammatic detail of the rib top having outside rib wales 9, 10, 11, and 12 and inside rib wales 13, 14, 15, and 16 of body yarn 17. The body yarn may be changed for horizontal striping as in said Larkin Patent 30 1,772,400. The wrap design threads are shown in wales 9, 11, and 12 at 23, 24, and 25. At certain courses the wrap threads are plated on the body stitches, as for example in course 18 at wale 9, and in other courses the wrap threads are floated 35 in back of the body stitches, as for example in course 19 at wale 9. This is well known as disclosed in said Larkin patent.

40 The rubber yarn inlay is shown at 26 extending horizontally between the outside and inside rib wales and being substantially hidden thereby. The beginning end portion of the rubber yarn is securely anchored by means of inter-knitting as single or unplied stitches 27 and 28 with the adjacent outside body yarn stitches of 45 courses 18 and 19 in wales 10 and 11. Likewise the end portion of the rubber yarn is anchored by stitches 29 and 30 between the courses 21 and 22 of the body yarn in the wales 10 and 11. It is obvious that the rubber yarn stitches may be in more than two wales if desired, to give additional security in anchoring the ends. It is also obvious that the end portions of the rubber yarn may be anchored in other ways, for example the 50 55

stitches 27 and 28 and 29 and 30, instead of being single yarn stitches interknitted between body yarn stitches in the wales 10 and 11, may be plated over the appropriate body yarn stitches 5 in which case the body and the rubber yarns are knitted together.

In wales 9, 11, and 12 it will be seen that the wrap threads extend in back of the rubber inlays, both when floating in unknitted relation to the body stitches and also when passing from one body stitch to an adjacent one in plated relation thereto, as particularly shown in wale 12. This binds the rubber inlay securely between the wrap thread and the outside rib wales.

15 In Fig. 1 is shown the relation of the rubber inlay to the rib stitches and to the wrap thread stitches in a design portion of the rib top such as at 4. At both 5 and 6, where the wrap designs are absent, the relation of the rubber inlay to the rib stitches is similar to that shown in Fig. 1, and with the exception of the absence of the wrap threads, is in all other respects identical therewith.

I claim:

25 1. A tubular stocking having a rib top comprising outside and inside rib wales and a rubber yarn garter inlay extending between the rib wales for one or more courses, an end portion of the rubber yarn being interknitted by means of 30 one or more single yarn stitches with the body stitches.

2. A tubular stocking having a rib top comprising outside and inside rib wales and a rubber yarn garter inlay extending between the rib wales for one or more courses, an end portion of the rubber yarn being interknitted by means of 35 single yarn stitches with the body stitches of a plurality of the outside rib wales.

3. A tubular stocking having a rib top com-

prising outside and inside rib wales and a rubber yarn garter inlay extending between the rib wales for one or more courses, an end portion of the rubber yarn being interknitted by means of one or more single yarn stitches with the body 5 stitches in single courses.

4. A tubular stocking having a rib top comprising outside and inside rib wales and a rubber yarn garter inlay extending between the rib wales for one or more courses, an end portion 10 of the rubber yarn being interknitted by means of single yarn stitches with the body stitches in single courses of a plurality of the outside rib wales.

5. A tubular rib top comprising outside and 15 inside rib wales and a rubber yarn garter inlay extending between the rib wales for one or more courses, an end portion of the rubber yarn being interknitted by means of one or more single 20 yarn stitches with the body stitches.

6. A rib knitted ground fabric made up entirely of wales and courses of textile yarn stitches and a rubber yarn incorporated in and extending coursewise of said ground fabric, an end portion of the rubber yarn being interknitted by means 25 of one or more single yarn stitches with the body stitches.

7. A rib fabric comprising outside plain and inside rib wales knit of a body yarn and a rubber yarn inlay extending coursewise between the 30 outside and inside rib wales for one or more courses, in certain of the wales portions of the rubber yarn being interknitted by means of single yarn stitches, with the two immediately adjacent stitches of the correspondingly adjacent 35 courses of the body yarn in the said certain wales, the other portions of the rubber yarn being inlaid unknit.

WILLIAM J. LONGTIN.
